Patented Mar. 27, 1928.

UNITED STATES PATENT OFFICE.

GEORGE W. P. OVERMAN, OF NORFOLK, VIRGINIA.

LIFEBOAT-RELEASING DEVICE.

Application filed January 21, 1926. Serial No. 82,704.

This invention relates to life boat releasing devices, and has for one of its objects the provision of a novel device of this character which shall comprise comparatively few parts and can be readily secured to a life boat and which can be easily operated to effect the prompt and positive release of the life boat after it is afloat.

With the foregoing and other objects in view, the invention consists of the novel construction, combination and arrangement of parts hereinafter fully described and claimed, and illustrated in the accompanying drawings, wherein:

15 Figure 1 is a view in side elevation illustrating the application of a life boat releasing device constructed in accordance with my invention,

20 Figure 2 is a top plan view of one of the units of the life boat releasing device,

Figure 3 is a vertical sectional view taken on the planes indicated by the line 3—3 of Figure 2, the hook of the unit being shown in active position,

25 Figure 4 is a similar view with the hook in inactive position,

Figure 5 is an inner edge view of one of the units of the device,

30 Figure 6 is a sectional view taken on the planes indicated by the line 6—6 of Figure 3,

Figure 7 is a detail perspective view of one of the latches of the device, and

Figure 8 is a detail perspective view of one of the hooks of the device.

35 Corresponding and like parts are referred to in the following description, and designated in the several views of the accompanying drawings, by similar reference characters.

40 To illustrate the application of the invention, there is shown in the drawings, the keel, bow and stern posts of a life boat which parts are designated respectively 1, 2 and 3.

The life boat releasing device embodies 45 similar units of which one is secured to the bow post 2 and the other to the stern post 3. Each unit comprises a bracket casing 4 which is substantially U-shaped in plan and has its inner vertical edge closed and its outer vertical edge open, a hook 5 pivoted within the casing 4 by a bolt 6, and a latch 7 pivoted within the casing 4 by a bolt 8. The casings 4 are secured at their open vertical edges to the bow post 2 and stern post 3 by 50 rivets 9 or other suitable attaching elements. The casings 4 extend inwardly from the bow

post 2 and stern post 3, and are so applied to these parts that the outer portions of their sides contact with opposite sides of said parts. The normal distance between the 60 sides of the casings 4 is greater than the thickness of the bow post 2 and stern post 3, and the outer portions of said sides are drawn inwardly during the application of the casings. In order to maintain those portions of the sides of the casings 4 that are located inwardly beyond the bow post 2 and stern post 3 in parallel relation, whereby to prevent any binding action on the hooks 5 and triggers 7, spacing sleeves 10 are positioned between the sides and secured in place by rivets 11 or similar elements. The spacing sleeves 10 contact with the inner edges of the bow post 2 and stern post 3 and assist the elements 9 in supporting the casings 4 75 in proper position.

The casings 4 are also open at their upper and lower edges, and the hooks 5 extend through the upper edges of the casings 4. When the hooks 5 are in active position, 80 their bills 5^a contact with the inner edges of the bow post 2 and stern post 3 and said posts maintain the shackle pin or fall hook 12 in engagement with the hooks when the latter are in active position. The lower edges of the bills 5^a are provided with arcuate portions 5^b and substantially straight portions 5^c, the latter being arranged in advance of or outwardly beyond the former. This peculiar formation of the lower edges of the 85 bills 5^a provide for a gradual release of the shackle pin or fall hook 12 until it reaches the straight portions of said edges whereupon the release is instantaneous. The latches 7 have weighted lower ends, and 90 their upper ends are adapted to contact with shoulders 5^d on the hooks 5 to effect the holding of the hooks in active position. The latches 7 are under constant urge in the direction of their active position due to their 95 weighted lower ends, and their movement in this direction, when the hooks 5 are in active position, is limited by lugs 5^e depending from the lower ends of the hooks 5 outwardly beyond the shoulders 5^d. The movement of the latches 7 in this direction, when the hooks 5 are in inactive position, is limited by the inner curved edges 5^f of the hooks 100 and the outer curved edges 7^a of the latches. The curved edges 5^f and 7^a of these parts 110 permit the hooks 5 to readily move into shackle pin or fall hook releasing position

when the latches 7 are retracted or moved into hook restraining position. Chains 14 or other suitable pull elements are connected to ears 7^b projecting from the lower inner corners of the latches 7. The chains 14 pass over guide or direction pulleys 15 and thence downwardly through the lower open edges of the casings 4. The pulleys 15 are located within the casings 4 near the lower ends thereof and forwardly beyond the pivots 8, and are supported for rotation preferably by bolts 16. If desired, the chains 14 may be connected to a lever, not shown, situated near the stern of the boat so as to permit the simultaneous retraction of the latches 7.

From the foregoing description, taken in connection with the accompanying drawings, it will be seen that the device may be readily secured to the bow and stern posts of a life boat, that the hooks 5 will be positively held in active position and will when in such position cooperate with the bow and stern posts to maintain their engagement with the shackle pins or fall hooks, that the latches may be readily retracted, and that on the retraction of the latches the hooks will quickly move into shackle pin or fall hook releasing position. The latches 7 are completely housed by the casings 4, and due thereto there is no possibility of their being accidentally retracted.

It should be understood that the drawings are merely illustrative and do not pretend to give exact proportions. Furthermore, the said drawings are illustrative of a preferred construction, it being my expectation that various changes and modifications may be made without departing from the spirit and scope of my invention.

40. What is claimed is:—

1. A boat releasing device comprising a bracket member, a hook pivoted to the bracket member and provided at its upper end with an outwardly directed bill and at 45 its lower end with a shoulder and a lug located outwardly of and extending below the shoulder, and a latch pivoted between its

ends to the bracket member and having a weighted lower end adapted to hold its upper end in contact with the shoulder and 50 lug.

2. A life boat releasing device comprising a bracket member, a hook pivoted between its ends to the bracket member, said hook being provided above its pivot with an outwardly directed bill and below its pivot with a shoulder and a lug located outwardly of and extending below the shoulder, and a latch pivoted between its ends to the bracket member below the pivot of the hook and 60 provided with a weighted lower end adapted to hold its upper end in contact with the shoulder and lug.

3. A life boat releasing device comprising a bracket member, a hook pivoted to the 65 bracket member and provided at its upper end with an outwardly directed bill and at its lower end with a shoulder, and a latch pivoted between its ends to the bracket member and having a weighted lower end adapted to hold its upper end in contact with the shoulder, the pivot of the latch being located below and inwardly of the pivot of the hook and the inner edge of the hook and the outer edge of the latch being curved to 75 permit the hook to move into releasing position when the latch is pulled outwardly.

4. A life boat releasing device comprising, in combination with the post of the boat, a bracket casing open at its outer, upper and 80 lower edges and having the outer portions of its sides contacting with the sides of the post, attaching elements passing through the post and said outer side portions of the bracket casing, spacing elements positioned 85 between the sides of the bracket casing and contacting with the inner edge of the post, a hook pivoted within the bracket casing, and a latch pivoted within the bracket casing and adapted to maintain in the hook in 90 active position.

In testimony whereof I affix my signature.

GEORGE W. P. OVERMAN.
